UNITED STATES PATENT OFFICE.

JOSEPH S. VAN GIESEN, OF LITCHVILLE, NORTH DAKOTA.

CONCRETE-CONSTRUCTION FORM.

1,119,734.

Specification of Letters Patent.

Patented Dec. 1, 1914.

Application filed November 18, 1913. Serial No. 801,653.

To all whom it may concern:

Be it known that I, JOSEPH S. VAN GIESEN, a citizen of the United States, residing at Litchville, in the county of Barnes and State of North Dakota, have invented certain new and useful Improvements in Concrete-Construction Forms, of which the following is a specification.

My invention relates to construction forms for concrete work, and more particularly to a type of forming means for upright concrete work in which the same elements may be readily elevated as the work progresses.

The object is to provide a simple and inexpensive means of the aforementioned character in which the outlay for material will be minimized, and in which the forming means may be used over and over again without alteration or injury save for ordinary wear and tear.

The improvement consists broadly of a plurality of rows of horizontally disposed forming boards, the said rows being placed one above the other edgewise, and on both sides of a space the desired thickness of a wall, together with vertical means for supporting the said forming boards, and a portable or adjustable working platform.

With these and other objects in view, all of which will be clearly explained and claimed, the improvement further resides in the novel arrangement of parts best seen by reference to the drawings forming a part of this application. But before referring specifically to the several features as shown in the drawings in which like reference characters represent like parts in the several views, I wish it understood that I do not intend to limit myself to the specific construction shown therein, but on the other hand shall expect to use any kind of material and any shape of forms and to make all such mechanical changes in the construction of the forming means as may be required to meet all other forms of construction not here illustrated, to which the broad principles of my invention may be applied.

In the drawings, Figure 1 represents an assembled view of one form of a concrete forming means for a straight wall. Fig. 2 is a transverse section of the same type of forming means as shown in Fig. 1 when the wall is partly constructed and showing the method of procedure. Fig. 3 is a view of a form of clamping means for the shaft of a hoisting windlass used in connection with

the construction work. Fig. 4 is a sectional plan view on the line A—B of Fig. 2 showing a method of bolting the studding or upright supports and the means of supporting the sliding retaining keys for the form boards. Fig. 5 is a plan view of an arrangement of my principle in connection with the construction of a hollow circular shaft. Fig. 6 is an elevation of the arrangement shown in Fig. 5, and, Fig. 7 is an arrangement for the spacing of forms used in certain constructions, C indicating the forms and D the spacer.

Referring to the parts specifically and by the reference characters, 1—1 are the studs or upright supports having slidably mounted over each two keys or key members 2—2, the same being joined at the top in any suitable manner by the jointing means 3. Key blocks 4 are mounted upon the sides of the studding in sufficient number to guide and support the sliding keys against the backward pressure of the green concrete, the said key blocks or supports being disposed a sufficient distance back from the "wall edge" of the studding to allow for the thickness of the form boards 5 as well as the sliding keys, (see Fig. 4), thus presenting a perfectly smooth inner surface for a flush wall.

Secured to the outer edge of the studding (the edge farthest from the wall) in any approved manner is the supporting rack 6. This rack serves the purpose of taking the downward thrust of the platform support 7 which support is pivotally mounted at 8 to the working platform 9. The platform is further provided with beams 10 which extend rearwardly from the pivoting point 8 of the support 7 to another pivoting support 11 on the sides of the sliding keys 2. Mounted directly over the working platform is the windlass 12 provided with rotating crank 13, retaining pawls 14, connecting ropes 15 and counter weights 16, the windlass being rotatably mounted upon the upright studding 1 by means of clamps (see Fig. 3) having a plurality of teeth 17 registering with similar teeth 18 of the rack 6 in such a manner that the said clamp may be readily shifted to any desired height within bounds of the rack. The said clamp is further provided with a flanged side wall 19 in which is an opening 20 the said opening being for the purpose of receiving a retaining screw which may be driven into the

studding for further retaining the said clamp. The cylindrical bearing 21 is for the obvious purpose of rotatably mounting the windlass spindle. Springs 22 may be disposed about as shown between the platform supports for the purpose of automatically controlling the supporting members. Rods or bolts 23 running from stud to stud through the plane of the proposed wall 5 serve the purpose of steadyng and securing the studs. These bolts may be provided with nuts at their extreme ends for the purpose of removing the said studs as the work progresses. It will be seen that by this arrangement of forming means any height of wall may be constructed with the equipment shown in Fig. 1 (of course assuming the working platform to be in both sections of the "rig" instead of in one as shown). 10 The method of procedure would be to fill up the forms there shown to the top; elevate the sliding keys after the cement was set, by operation of the windlass; then remove the form boards and replace the same near 15 the top of the wall, as in Fig. 2. This operation would be repeated until the work had reached the limits of the present disposition of the studding, at which stage the said studding would be elevated as is shown 20 in Fig. 6, use being made of the protruding ends of the bolts previously left in the finished portion of the wall for support. Obviously the arrangement shown in Fig. 1 may be carried on indefinitely to suit any 25 height of wall required, and that right angle corners, curved corners, offsets or any irregularities to suit conditions may be made by a different disposition of the studding. Elevated structures such as towers, piers, 30 smokestacks or the like may be constructed with an arrangement as shown in Figs. 5 and 6, while cisterns, wells, and all sunken shafts may be constructed in substantially the same manner except that the supports for 35 the windlass could be disposed upon the ground instead of upon the studding.

It may be necessary until the first course of cement is poured and set to provide a longitudinal supporting means for the vertical members of my arrangement. I therefore show for the sake of illustration a connecting cable 24 disposed as shown, for that purpose, the ends of which are supposed to be secured to the ground. It is obvious, however, that I may see fit to join the members in any other approved manner and remain within the spirit of my invention.

Having thus described my invention, its advantages over the present manner of procedure become apparent. The saving in time of erection, not to mention the saving in material, is enormous. On large buildings where the forming means are used repeatedly it is necessary with the old method 60 to continually supply new material to replace timbers split and broken by erection and removal, while with my improved arrangement and method these disadvantages 65 are overcome.

70 I claim as my invention and desire to secure by Letters Patent of the United States:

In a forming and constructing means for concrete work, the combination of a plurality of vertically disposed supporting studs, means for retaining the studs in predetermined relative positions, vertically 75 slideable key members carried by the said studs, a hoisting means for the key members 80 secured to the said studs, connecting means between the said hoisting means and the said slideable key members, a supporting toothed rack secured to the said studs, and a working platform supported by the said 85 key members and the said rack.

In testimony whereof I affix my signature in presence of two witnesses.

JOSEPH S. VAN GIESEN.
